UNITED STATES PATENT OFFICE

STEPHEN E. CIBULAS, OF BRIDGEPORT, CONNECTICUT

VENTILATOR

Application filed January 24, 1928. Serial No. 249,036.

This invention relates to ventilators, particularly of the type to be connected to a room to be ventilated by a passage leading through the roof, but it is by no means limited to such specific use as it may be employed for ventilating any desired enclosed space.

It has for an object to provide a simple and improved construction which will effectively ventilate the space desired without the use of moving elements.

It is also an object of the invention to provide a simple structure which will be snow and water proof and which will have a great discharge capacity.

15 It is a further object of the invention to provide a ventilator which will perform its function of sucking or drawing air or fumes from the space to be ventilated no matter from what angle or direction the wind may be blowing. It will also function to withdraw these fumes whether the wind blows or not.

With the foregoing and other objects in view, I have devised the construction illustrated in the accompanying drawing forming a part of this specification. In this drawing,

Fig. 1 is a partial side elevation and a partial vertical section of my improved ventilator, and with arrows showing its operation when the outside air or wind is moving downwardly with respect to the ventilator, and

30 Fig. 2 is a vertical section similar to the section of Fig. 1 but indicating its action when the wind is moving upwardly.

The ventilator structure shown comprises an upright conduit 5 which is open at its upper end and connected to the space to be ventilated, such as the room 6 of a building, and

40 I have shown the ventilator as mounted on the roof 7. Over the open upper end of the conduit 5 is mounted a hood 8 which may be of different shapes, but is preferably substantially conical as shown, and it is of a size so that its lower edge extends some distance outwardly beyond the rim of the conduit 5. This hood is spaced a sufficient distance above the open end of the conduit to provide a clear passage for flow of air or other gases outwardly from the conduit.

Enclosing this space between the hood and conduit are a plurality of upright ring vanes 9, 10, 11, 12 and 13 which are spaced from the hood and conduit and from each other to provide upright air or wind passages outside of and across the passage between the hood and conduit. In the specification and claims where it is desirable to distinguish the ring vane 11 from the other vanes I have called this particular vane a "ring baffle". It will be noted that the vane 9 encloses the lower edge of the hood 8 and is spaced therefrom so as to form a passage between them, while the second vane 10 encloses the lower edge of the vane 9 and is spaced from the first vane to form an upright passage. The vanes 12 and 13 are similar to the vanes 9 and 10 but the vane 13 encloses the upper edge of the conduit 5 and is spaced therefrom while the vane 12 encloses the upper edge of the vane 13 and is spaced therefrom. Still further, the vanes 12 and 13 are spaced from the vanes 9 and 10 to provide horizontal air passages between them, while the vane or baffle 11 is spaced outwardly from the vanes 10 and 12 and closes the space between them, that is, it overlaps the lower edge of the vane 10 and the upper edge of the vane 12. It is to be understood that although I have shown two vanes between the outer vane or baffle 11 and the hood, or this outer vane and the conduit, I am not limited to any specific number as one or more of these vanes may be employed depending on the size of the structure. By using a greater number of vanes we can secure a greater outflow or capacity for discharge of air and gases without having any straight direct passage to the conduit for entrance of snow or rain.

45 About the upper portion of the conduit is a sweat gutter 14 for collection of condensation and which has openings 15 discharging to the roof. Within the conduit may be provided a damper 16 of any suitable type for controlling the ventilating effect or vary the capacity of the conduit.

50 From reference to the drawings it will be seen that no matter in which direction the wind is blowing its passage through the spaces between the vanes, and between these

vanes and the hood and conduit, will draw air and gases from the conduit. For example, as indicated by the arrows 17 in Fig. 1, downward flow of the air through the upright passages at the sides of the vanes will create a suction on the air and gases in the conduit 5 represented by the arrows 18 and will draw these gases out, and will thus ventilate the space with which the conduit is in communication. Referring to Fig. 2, if the wind represented by arrows 19 flows in the opposite direction or upwardly it will have the same effect on the gases in the conduit, and, of course, there will be the natural draft through the ventilator if there is no wind blowing. This construction of ventilator is very simple and has a large capacity, with large exit passages which are effectively controlled against entrance of rain or snow. The vanes and hood may be supported on the conduit 5 in suitable spaced relation by means of supports or brackets 20. The various elements may be secured to these supports or brackets by bolts, rivets or spot welding, and the number of supports may be as found desirable.

Having thus set forth the nature of my invention, what I claim is:

1. A ventilator comprising an upright conduit, a hood over the top of the conduit and spaced therefrom, a plurality of spaced upright ring vanes arranged with the inner one enclosing and extending above and below the upper end of the conduit and spaced therefrom and the next outer vane enclosing and extending above and below the upper edge of the next inner vane, a plurality of similar spaced upright ring vanes arranged with the inner one enclosing and extending above and below the lower edge of the hood and spaced therefrom and the next outer vane enclosing and extending above and below the lower edge of the next inner vane, the upper vanes being flared outwardly at their upper ends and the lower vanes being flared outwardly at their lower ends, and an upright outer ring baffle spaced from and enclosing the adjacent edges of the outer vanes.
2. A ventilator comprising an upright conduit, a hood over the top of the conduit and spaced therefrom, said hood being of sufficient diameter to extend outwardly beyond the periphery of the conduit, a plurality of spaced upright ring vanes arranged with the inner one enclosing and extending above and below the upper end of the conduit and spaced therefrom and the next outer vane enclosing and extending above and below the upper edge of the next inner vane, a plurality of similar spaced upright ring vanes arranged with the inner one enclosing and extending above and below the lower edge of the hood and spaced therefrom and the next outer vane enclosing and extending

above and below the lower edge of the next inner vane, a sweat gutter extending upwardly and outwardly from the outer wall of the conduit and forming a baffle between the lower ring vane and the upper end of the conduit, and an upright outer ring baffle spaced from and enclosing the adjacent edges of the outer vanes.

In testimony whereof I affix my signature.

STEPHEN E. CIBULAS.
